UNITED STATES PATENT OFFICE

2,453,626

TRANSPORTATION LOAD AND METHOD OF
PREPARING THE SAMEDon F. Hedges, Crown Point, Ind., assignor to
Carnegie-Illinois Steel Corporation, a corpora-
tion of New Jersey

Application October 2, 1944, Serial No. 556,839

2 Claims. (Cl. 105—367)

1

This invention relates to a transportation load and method of preparing the same and is especially adapted for heavy strips, deformed bars, and like material which are longer than a railway car. In shipping this long material it is necessary to resort to what is known as double or triple car loading in which an empty car is inserted in the train, the long material from a loaded car projecting over the empty car. In preparing such loads it is necessary to so load the car that the load will be solidly held together, will not shift in transit, and will be in units of a size that can be handled by both the shipper and the receiver. It should be easy to put the blocking and strapping in place and to remove it without damaging the car or material. Formerly the load was fastened to the floor by long bolts which passed through holes in the floor and to which nuts were screwed beneath the car. To insure that these bottom nuts did not come off it was necessary to burr the threads on the lower ends of the bolts and this made it difficult to unload the car.

It is an object of this invention to prepare the load so that the car will not be damaged.

Another object is to prepare the load so that the minimum of time, labor and material is required.

These and other objects will be more apparent after referring to the following specification and attached drawings, in which:

Figure 1 is a schematic showing of triple car loading;

Figure 2 is a top plan view of the load;

Figure 3 is a side elevation taken on the line III—III of Figure 2; and

Figure 4 is a sectional view taken on the line IV—IV of Figure 2.

Referring more particularly to the drawings, the reference numeral 2 indicates gondola cars on each side of a flat car 4. The long objects 6 are arranged on the gondola cars 2 with their ends extending over the flat car 4. In preparing the long objects for transit they are assembled and strapped together to form units 6 which are of convenient size for handling with the equipment available to both shipper and customer. Cross timbers 8, 10 and 12 are then nailed to the car floor 14, the cross timber 8 being of less thickness than the cross timber 12 and center cross timber 10 being of less thickness than the average of the end cross pieces 8 and 12. This allows for some deflection of the bundles at timber 10 so as to raise the overhanging end over the empty car 4 to provide additional clearance between the

2

overhanging load and the floor 16 of the empty car. Bundles A, B and C are then placed on the cross timbers with their ends extending from the car 2 over the car 4 with sufficient space between the bundles for insertion of vertical separators 18 and the bundles moved close together with the separators 18 therebetween. Horizontal separators 20 are then laid on the first layer of bundles and a second layer of bundles are placed on the horizontal separators 20 against the vertical separators 18. Additional horizontal separators and layers of objects are added until the car is loaded, the number of layers depending upon the size of the bundles. The vertical separators 18 on the end overhanging the car 2 do not rest on the floor of the car and therefore cleats 22 resting on top of the load are spiked thereto. When the loading is completed, straps 24 are placed around the load on both sides of and close to each set of separators and are stretched taut and clamped in place. Cleats 26 are then positioned and solidly spiked against the bottom bundles to prevent movement of the load sideways. Positioning the straps 24 close to the separators insures solid lashing of the bundles since the bumping and jolting of the car causes very little spring at this point.

While one embodiment of the invention has been shown and described, it will be apparent that other adaptations and modifications may be made without departing from the scope of the following claims.

I claim:

1. The method of preparing a transportation load of a plurality of bundles of slightly flexible heavy strips or the like which are longer than a railway car for transit therein which comprises fastening end cross timbers to the floor of the car, the timber at one end being thicker than at the other end, fastening a center cross timber of less thickness than the average thickness of the end cross timbers to the floor of the car, placing a plurality of bundles on the cross timbers with their ends extending unsupported from the car at the end having the thickest cross timber, placing vertical separators between the bundles, moving the bundles closely together with the separators therebetween, laying horizontal separators on the first layer of bundles adjacent the vertical separators, placing a second layer of bundles on the horizontal separators against the vertical separators, continuing adding horizontal separators and layers of bundles until the car is loaded, placing straps around the load on both sides of and close to each set of separators, and fastening cleats

against the bottom layer of bundles to prevent transverse movement of the load.

2. A transportation load of a plurality of bundles of slightly flexible heavy strips or the like which extend longitudinally of a railway car with one end extending unsupported therefrom, comprising three cross timbers of varying thickness fastened to the floor of the car, the center cross timber being of less thickness than the average of the end cross timbers, a plurality of layers of the bundles resting on said cross timbers with their ends extending from the car at the end having the thickest cross piece, said bundle sagging in the middle so as to raise the overhanging end thereof, vertical separators between the bundles in each layer, horizontal separators between each layer adjacent the vertical separators, and straps around the load close to each set of separators.
